MUSIC SHEET TURNER

Charles Gaines, Vallejo, Calif.

Application August 26, 1946, Serial No. 693,023

1 Claim. (Cl. 84—501)

1

This invention relates to an improved music sheet turner and has particular reference to an especially constructed device to be used by musicians when playing in orchestras and the like for holding music composition sheets and which is provided with means, whereby the player can turn the sheet while playing without the necessity of using his hands, thus leaving his hands completely free to play the musical instrument at all times.

The primary object of the present invention is to provide a device of the character described which will turn a sheet of music through the medium of a foot pedal.

Another object of the present invention is to provide means for removably and adjustably attaching the device to a conventional music stand, whereby the device can be easily removed and is readily adjustable to different heights.

A further object of the present invention is the provision of an especially constructed frame for holding the music sheets and a clock spring for turning the same.

A still further object of the present invention is the provision of a resilient bumper for cushioning any and all noise produced by turning the sheets.

A still further object of the present invention is to provide a device of the character described that is durable, simple in construction, economical to manufacture, efficient in operation and highly serviceable in use.

Other objects and advantages will be apparent during the course of the following description.

In the accompanying drawings forming a part of the specification, wherein for the purpose of illustration like numerals designate like parts throughout the same,

Fig. 1 is a perspective view of the device shown in its normal position on a conventional music stand,

Fig. 2 is a perspective view similar to Fig. 1, except showing the device in the act of turning a sheet of music.

Fig. 3 is a front elevational view of the music sheet holding means and the mechanism for turning the same,

Fig. 4 is a top plan view of the device,

Fig. 5 is a side elevational view, looking at Fig. 5 in the direction of the arrow 5.

Referring in detail to the drawings and to the various parts thereof, the numeral 8 designates a conventional music stand, as a whole, the numeral 9 the holder and the numeral 10 a standard tripod for supporting the same. The improved

2

device includes an auxiliary holder for retaining the music sheets and comprises a back or base member 11 for holding the cover portion of the music and a frame or leaf designated as a whole by the numeral 12 for retaining the center sheet. Practically all musical compositions consist of a cover portion and a center sheet.

The composition is written on the inside of the cover designated in Fig. 2 by the numerals 13 and 14 and on both sides of the center sheet designated by the numerals 15 and 16. The said frame 12 is made of any suitable material such as plastic or metal, the present illustration showing a wire frame, the numeral 17 designating a substantial wire bent into a rectangular form and the numeral 18 a pair of thin cross wires that are preferably spot welded thereto. It is very important that the said frame 12 be sufficiently transparent for permitting the music to be read through the leaf. A plurality of suitable clips 19 and 20 shown to advantage in Figs. 3 and 5 are welded to the frame 12 or otherwise substantially fixed thereto for holding the music sheet thereon. It will be noted that the outer clips 19 have slots 19' extending longitudinally with respect to the back 11 and the central clips 20 have slots 20' extending at right angles to the outer clips. One of the said central clips is preferably adjustable as indicated at 21 for accommodating different widths of sheets. The back 11 is provided with a pair of clips 22, which clips are hingedly secured to the outer end portions of the back as shown at 23 in Fig. 3, for holding the cover portion of the music thereon. The cover portion of the music is retained onto the back 11 by the clips 22 and the center sheet is retained onto the frame 12 by the clips 19 and 20.

An elongated metal strap 24 is transversely positioned across the central portion of the back 11 and is fixed thereto by suitable screws or rivets 24' as shown to advantage in Figs. 3 and 5. The said strap 24 extends beyond one edge of the back 11 and the outer extremities thereof are bent at right angles to the back as indicated at 25 and 26 forming two oppositely opposed overhanging lips as shown in Fig. 5. A pair of hinge plates 27 and 28 are welded to the frame 12 and are hingedly secured to the said ends 25 and 26 by suitable pins 29 and 30. An angular member 31 is fixed to the outer extremity of the strap 24 and extends over the plate 28 and in parallelism therewith. A threaded nut 32 rigidly secures the pin 30 to the said angular member 31.

The preferred means provided for turning the frame 12, whereby the sheet thereon is inverted,

consists of a suitable clock spring 33 the inner end of which is fixed to the pin 30, the outer end extending against the rod 34 of the frame, as shown to advantage in Figs. 3 and 4, whereby a resilient tension is applied against the frame in direction of the arrows A for turning the same. A hook 35 is hingedly secured to the back 11 as at 36 and a curved spring 37 hingedly secured to the said back 11 as at 38 resiliently holds the said hook against the pin 39 and in which position the said hook overlaps the lower end portion of the frame 12 retaining the said frame against the back as illustrated in Figs. 1 and 3. The said pin 39 can be bent over to form a guide for the said hook 35 if desired. The said hook is controlled by a foot pedal mechanism illustrated to advantage in Figs. 1 and 2. The said mechanism includes a foot pedal 40 having an elongated round rod 41 extending therefrom, which rod is bent, forming a crank as at 42 and is pivotally connected to a tubular member 43 as at 44. A secondary tube 45, having a smaller diameter than the tube 43 is telescopically mounted therein and the outer extremity of the said secondary tube 45 is fixed to a flexible cord or wire 46 which is connected to the hook 35 as shown to advantage in Figs. 1, 2 and 3. A thumb screw 47 functions to adjustably lock the tubes 43 and 45 together. A horizontal strap 48 having bent portions forming lips 49 and 50, which lips are apertured for receiving the foot pedal rod 41, is provided for revolvably supporting the said foot pedal rod. A sleeve 51 is welded to the said strap 48 and a conventional thumb screw 52 functions to removably and adjustably secure the said sleeve onto the tripod 10 of the music stand. As the music stand is adjustable to different heights it is obvious that the mechanism connecting the foot pedal to the hook 35 for controlling the turning of the music sheet is adjustable accordingly.

From the foregoing description taken in conjunction with the accompanying drawing it will readily be seen that the hook shaped lever 35 and mechanism associated therewith provides a suitable means for locking the frame 12 and releasing the same and that the clock spring 33 is positive in its action. The foot pedal 40 permits the musician to turn the sheet of music by simply pressing the pedal with the foot, whereby the hands are completely free at all times to play the musical instrument and the possibility of getting out of time with the music due to the necessity of turning the sheet of music

with the hand is positively eliminated. The numeral 53 designates suitable resilient or flexible bumpers for cushioning any noise that might be made when the frame 35 is turned.

It is to be understood that the form of my invention herewith shown and described is to be taken as a preferred example of the same and that various changes relative to the shape, size, material and arrangement of parts may be resorted to without departing from the spirit of the invention or the scope of the subjoined claim.

Having thus described my invention, I claim:

A device of the character described for supporting and turning a musical composition embodying a folded sheet and a center sheet, said device including in its construction a music stand, a back positioned at the upper portion thereof for retaining the folded sheet of music, a frame hinged to the said back at the central portion thereof for retaining the center sheet of music, a clock spring secured to the said back and positioned above the same, said clock spring being capable of engaging the frame for turning the frame from one lateral side to the opposite lateral side of the back, a resiliently held hook shaped lever hingedly secured to the said back at the lower portion thereof for normally retaining the said frame on one lateral side of the said back, a foot pedal pivotally secured to the music stand, a crank arm leading from the foot pedal, a tubular member pivotally connected to the said crank arm and extending upwardly therefrom, a second tubular member telescopically positioned in the first mentioned tubular member, means adjustably securing the said tubular members together, and flexible means connecting the second mentioned tubular member to the said hook shaped lever, whereby the operating of the said lever for releasing and turning the frame is facilitated.

CHARLES GAINES.
